UNITED STATES PATENT OFFICE.

CHARLES V. KAHOA, OF RUSSELL, IOWA, ASSIGNOR OF ONE-HALF TO J. H. HANCOCK, OF BEARCREEK, MONTANA.

PORTABLE HAY-STACKER.

No. 928,232.

Specification of Letters Patent.

Patented July 13, 1909.

Application filed December 17, 1908. Serial No. 468,402.

To all whom it may concern:

Be it known that I, CHARLES V. KAHOA, a citizen of the United States of America, and resident of Russell, Lucas county, Iowa, have invented a new and useful Portable 5 Hay-Stacker, of which the following is a specification.

The object of this invention is to provide improved means for stacking hay.

10 A further object of this invention is to provide means for receiving, elevating, moving laterally and dumping a load or quantity of hay.

A further object of this invention is to 15 provide an improved construction for the carrier or fork of a hay-stacker.

A further object of this invention is to 20 provide improved means for holding the fork against tilting during the operation of elevating and moving laterally.

25 My invention consists in the construction, arrangement and combination of elements hereinafter set forth, pointed out in my claims and illustrated by the accompanying drawing, in which—

Figure 1 is a side elevation of the machine, the dotted lines illustrating the fork in elevated and dumping position. Fig. 2 is a plan of the machine, the dotted lines showing the fork or carrier turned laterally at 30 right angles to its initial position, preparatory to dumping the contents thereof. Fig. 3 is a cross-section on the indicated line 3—3 of Fig. 1 and Fig. 4 is a detail rear elevation illustrating the construction of parts of 35 the retaining and dumping mechanism. Fig. 5 is a cross-section on the indicated line 5—5 of Fig. 2. Fig. 6 is a cross-section on the indicated line 6—6 of Fig. 2 and 40 Fig. 5.

In the construction of the machine as shown, the numeral 10 designates a post or mast stepped at its lower end in a base 11 suitably anchored in desired location as by 45 stakes 12 driven in the ground. Guys 13, 14, 15, in this instance wire ropes, are pivotally connected to the upper end of the mast or post 10 and diverge therefrom. Loops 16 are formed in the lower ends of the guys 13, 50 14, 15 and embrace stakes 17, 18, 19 driven in the ground at distances from each other and from the base 11. Arms 20, 21 are pivoted at their inner ends on a bolt 22 extending through the lower portion of the post 10 55 and said arms extend outwardly in diverg-

ing planes from said post. Arms or extension bars 20^a, 21^a are mounted on and overlap the outer ends of the arms 20, 21 and are secured thereto slidably and adjustably by straps or stirrups 23. The outer end portions of the extension bars 20^a, 21^a are connected by a cross-bar 24. A fork is provided and is constructed of cross-bars 25, 26 crossing the extremities of the extension arms 20^a, 21^a, and tines or fingers 27 fixed thereto, crossing beneath and extending outward from said cross-bars. The cross-bar 25 is hinged or pivoted to the forward ends of the extension bars 20^a, 21^a, by means of pairs of inter-engaging eye-bolts 20^b, 21^b 60 (Fig. 5). Handles 28, 29 are fixed to and cross above and extend inward from the cross-bars 25, 26 and the inner ends of said handles are directly above the bars 20^a, 21^a. A bar 30 is slidingly mounted on the rear 65 face of the post 10 and is confined by keepers 31. A cable 32 extends through the lower end portion of the bar 30 (Fig. 4) and has its central portion slidingly engaged thereby. The end portions of the cable 32 extend 70 through guide sheaves 33 on opposite sides of the post 10 above the lower end of the bar 30, and thence along the arms 20, 21 and extension bars 20^a, 21^a and through guide sheaves 34 on the outer end portions 75 of said bars, and thence vertically to points of attachment to the inner ends of the handles 28, 29. A yoke 35 is mounted around the post 10, is bent to form a bell-crank and is fulcrumed to said post by a bolt 36. A 80 roller 37 is pivoted in the yoke 35 and crosses the rear face of the post 10 above the bar 30. The yoke 35 normally occupies the position shown in Fig. 1 with the roller 37 engaging the upper end of the bar 30 and preventing 85 upward movement of said bar.

It is the function of the bar 30, held by the yoke 35 and roller 37, to apply strain 90 through the cable 32 and hold the fork or carrier in horizontal position shown with the tines or fingers 27 in position to be loaded with hay by a bull-rake (not shown) in a common and well-known manner. A cord 38 is fixed at one end to one end of the yoke 35, extends through a sheave 39 on the post 10 above the yoke, and to a convenient position to be handled by an operator. Eye-straps 40, 41 are fixed to and project laterally of the cross-bar 24 and a cable 42 is fixed at its ends to said eye-straps. The 105 110

cable 42 extends through blocks 43, 44 arranged in pairs on opposite sides of the top and central portion, respectively, of the post 10, and the central portion of said cable 5 depends as a loop in front of said post and carries a pulley block 45 loosely suspended therein. A draft cable 46 is fixed at one end to an eye 47 on the pulley block 45 and extends downward along the post 10 and 10 through one portion of a double foot-pulley 48, fixed to the foot of the post, thence upward along the post and through said pulley block 45, thence downward along the post and through the other portion of the foot-pulley block, and thence to the rear of the post to a point of convenient attachment to 15 a draft animal or other hoisting power.

When the fork or carrier is loaded, draft is applied through the cable 46 to pull the 20 block 45 and bight of the cable 42 downward and cause the cable 42 to raise the outer ends of the extension bars 20^a, 21^a and the loaded fork thereon. As the fork is raised it is held in horizontal position, to 25 retain and carry the load, by the cable 32, bar 30 and yoke 35. When the fork has been raised to the desired degree, it, the arms connecting it to the post and the post itself are turned laterally, by manual actuation, to the desired position, such as indicated by dotted lines in Fig. 2, and then the bell-crank yoke 35 is tripped, by manual draft on the cord 38, to the release of the roller 37 from and the upward movement of 30 the bar 30. Thus the restraint of the cable 32 is released and the fork is permitted to tilt, under the weight of the load thereon, and dump its contents. A spring 49 (dotted lines Fig. 1) connecting the cross-bars 24 35 and 26 is expanded by tilting of the fork, and upon the dumping of the load from said fork said spring retracts and returns the fork to normal horizontal (though elevated) position and permits the automatic descent 40 of the bar 30 into locked position beneath the roller 37 of the yoke 35. The fork or carrier can be moved through any arc permitted by the guys 13 and 15 and said guys can be adjusted into any desired position 45 that will maintain the equilibrium of the post 10.

I claim as my invention—

1. A hay stacker, comprising a post stepped for rotary movement, guys pivoted

at their upper ends to said post, loops on 55 the lower ends of said guys, stakes in said loops, and adapted to be driven into the ground, extensible arms pivoted to the lower end of said post, a fork hinged to the outer ends of said arms, a bar slidingly mounted 60 on the post, a yoke fulcrumed on the post, a roller on the yoke engaging said bar, means for tripping the yoke, a cable connecting the bar and fork, and block and tackle connecting the post and arms whereby 65 the arms and fork can be raised and lowered.

2. A hay stacker, comprising a post stepped for rotary movement, means for bracing said post, arms pivoted to the lower end of said post, a fork hinged to the arms, 70 means for latching said fork in horizontal position, means for tripping the latching means, a cable fixed at its ends to the outer ends of the arms, pulleys on the post supporting said cable, the central portion of 75 said cable forming a pending loop in front of the upper end of said post, a pulley block suspended in the loop of said cable, a double foot-pulley block fixed to the lower end of the post, and a draft cable fixed to 80 the suspended pulley block, rove through the foot-block, rove through the upper block, again rove through the foot block and adapted for attachment to draft means.

3. A hay stacker, comprising a post stepped for rotary movement, means for bracing said post, arms pivoted to the post, a fork hinged to said arms, means for raising and lowering said arms and fork, a bar mounted for vertical reciprocation in sliding 85 engagement with said post, a cable fixed at its ends to said fork and having its central portion slidingly mounted through the lower end portion of said bar, guide sheaves on the arms and post engaging said cable, a 90 bell-crank yoke fulcrumed on the post, a roller on said bell-crank yoke crossing the upper end of said bar and adapted to be engaged thereby, and a cord attached to and adapted for oscillation of said bell-crank 95 yoke.

Signed by me at Russell, Iowa, this seventh day of November, 1908.

CHARLES V. KAHOA.
